UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY,

MACHINE FOR OPERATING UPON BLANKS OF SHEET MATERIAL.

Application filed May 14, 1920. Serial No. 381,470.

The present invention relates to machines for operating upon blanks of sheet material, and more particularly, to machines for skiving heel lifts and delivering them in stacked 5 formation ready for transferal to other machines in which they are to be used.

The object of the invention is to reorganize and improve the construction of machines of the character named, for the purpose of rendering them more efficient and reliable in operation. To the accomplishment of this object, and such others as may hereinafter appear, as will be readily understood by those skilled in the art, the present 10 invention comprises the features and combinations of parts hereinafter described and particularly pointed out in the appended claims.

The various features of the invention will 20 be best understood from a description of the preferred embodiment thereof illustrated in the accompanying drawings, in which:

Figure 1 is a plan view of the machine; Fig. 2 is a view in side elevation thereof; 25 Fig. 3 is a view, partly in vertical section and partly in side elevation, of the machine; Fig. 4 is a detail sectional view taken on the line 4—4 of Fig. 3; Fig. 5 is a detail view, in front elevation and on an enlarged scale, 30 showing means for insuring the feeding of a single lift only at a time from the supply magazine of the machine; and Fig. 6 is a section on the line 6—6 of Fig. 5.

The machine in its general organization 35 is similar to that shown in a co-pending application, Serial No. 142,474, filed January 15, 1917, by the present applicant, now Patent No. 1,381,318. Briefly stated, the present machine comprises, in common with the machine of said patent, a skiving mechanism; a feeding mechanism for automatically advancing the lifts from a supply magazine to the skiving mechanism; means for insuring the feeding of a single lift only 40 at a time from the supply magazine; a support across which the skived lifts are pushed, in series by the advance of the lifts from the skiving mechanism until they drop one by one from the end of the support into a receiving magazine; a lift-straightening or flattening device which prevents curling of the lifts as they leave the skiving mecha-

nism; and means, operating upon the skived lifts as they enter the receiving magazine, for stacking them therein. In the present 55 machine, however, certain improvements are embodied in the automatic feeding mechanism and an improved stacking device is employed which operates in a more efficient and reliable manner to stack the lifts in the 60 receiving magazine. In addition, the present machine is provided with a stabilizing device for facilitating the delivery of the lifts in succession from the support which extends between the skiving mechanism and 65 the receiving magazine. A device for tipping the lifts slightly, as they start to drop into the receiving magazine may be employed to insure that they will come to rest 70 therein in the proper position for the performance of the stacking operation; and various adjusting means are incorporated which are arranged to enable the machine to operate upon lifts varying widely in 75 dimensions.

Referring to the drawings, the various parts and operating instrumentalities of the machine are mounted upon a frame comprising a substantially rectangular body portion 10, having legs 12 (Fig. 2) which are adapted to rest upon a bench or other suitable support. The body portion 10 of the frame is provided with standards 14 rising from its opposite ends. A main power shaft 16 (Figs. 2 and 3) extends horizontally at the 80 rear of the machine and is journaled in bearings formed in a pair of arms 18 which project rearwardly from the body portion 10 of the frame. The power shaft 16 is provided with the usual fast and loose pulleys 85 20 and 22, which are adapted to receive a belt leading from a suitable source of power.

The skiving mechanism shown is of the general type commonly used in the manufacture of shoes to skive, split or even, 90 blanks of leather and comprises upper and lower feed rolls 26 (Fig. 3) and 28 respectively, and a skiving knife 30, which is horizontally mounted with its cutting edge projecting between said rolls. The periphery 100 of the lower feed roll 28 is serrated or roughened to facilitate the feeding of the blanks. The illustrated machine is designed for operating upon top lifts for heels and

hereinafter the blanks which the machine is adapted to skive will, for brevity, be termed "lifts". The trunnions of the lower feed roll 28 are journaled in adjustable bearings 32 which are acted upon by stiff springs 34 (Figs. 2 and 3) tending to force the roll upwardly toward the knife 30 and normally to hold the bearings 32 against suitable stops on the frame of the machine. The 10 trunnions of the upper feed roll 26 are journaled in bearing-blocks 36 (Fig. 2) which are vertically adjustable in ways in the frame standards 14 by means of inclined cam faces that are formed on a slide-bar 38 and normally serve to maintain the bearing-blocks in adjusted positions. The slide-bar 38 is actuated to adjust the bearing-blocks 36 in unison by means of a hand-wheel 40 that is fast on a shaft having a rack and pinion connection with the slide-bar. The skiving knife 30 is interposed between the flat upper surface of the body 10 of the frame and an inclined plate 42 which temporarily supports the skived lifts, the knife being rigidly secured in position by means of bolts 44 which extend through said lift supporting plate and through the knife.

The feed rolls 26 and 28 are driven from the power shaft 16 so that their adjacent surfaces move in the same direction and at the same rate of speed. To this end one of the trunnions of the lower feed roll has secured thereto, a large gear 46 which meshes with a small gear 48 that is fast on the power shaft. A second small gear 50 (Fig. 3) which is secured to the power shaft 16 at the opposite side of the machine, meshes with a small idler gear 52 which, in turn, meshes with a large gear 54 that is fast to one of the trunnions of the upper feed roll.

The lifts to be operated upon are stacked in a vertical column within a skeleton magazine 60 which is located at the front of the machine. The magazine 60 comprises a pair of upright wall members 62 and 64 (Figs. 2 and 3) which are mounted upon a magazine support 66, the latter extending across the upper part of the machine and being bolted to the frame standards 14. The upright magazine member 62 consists of a flat plate which is rigidly secured to the magazine support 66, the plate having a smooth, vertical front face for engaging and alining the breast edges of the stacked lifts. The upright magazine member 64 comprises a strip of sheet material which is bent to cause its rear face to conform somewhat to the contour of the curved rear edges of the lifts contained within the magazine. The member 64 is adjustably supported by a pair of horizontal bars 68 (Figs. 2 and 3) which are arranged one above the other and adapted to slide in guideways formed in the magazine support 66. The supporting bars 68 are severally provided with racks

70 which are operatively engaged by a pair of pinions 72 carried by a vertical shaft 74 that is journaled at its ends in bearings on the magazine support 66. Secured to the shaft 74, between the pinions 72, is a hand-wheel 76, by means of which the pinions may be turned to adjust the magazine member 64 toward or from the magazine member 62 and thus enable the magazine to accommodate lifts of different sizes. The lowermost lift of the stack within the magazine rests upon a horizontal table 80 which is provided, at its opposite lateral edges, with down-turned webs 82 (Fig. 1) that are secured to the frame of the machine. The magazine member 62 is arranged with its bottom edge spaced above the table sufficiently to permit the thickest lifts which may be operated upon to be fed from the bottom of the stack. The bottom edge of the magazine member 64 is located far enough above the table to permit the reciprocation beneath it of a feed-slide or pusher 84, by means of which the lifts are fed one-by-one to the skiving knife from the bottom of the stack in the magazine.

The construction of the feed-slide or pusher 84 is identical with that of the corresponding part shown in the patent hereinbefore mentioned, except that the forward end of the feed-slide is shaped, as shown in Fig. 1, to engage the rear or curved edges of the lifts at points on opposite sides of a medial line normal to the breast edge thereof. This particular construction tends to prevent the lift from tilting in a lateral edgewise direction as it is being fed by the pusher and tends to insure that the breast edge of the lift will be presented squarely to the grip of the feed rolls.

The feed-slide 84 is reciprocated horizontally in suitable guideways in the table 80 by means including a cam 86 (Fig. 2) that is fast to one side of the gear 46. The periphery of the cam 86 is adapted to engage a cam roll 88 carried by a connecting rod 90, one end of which is pivotally mounted on the adjacent trunnion of the lower feed roll, alongside of the cam 86, while the other end of the rod 90 is pivotally connected with an arm 92 that is adjustably secured to a rock-shaft 94. The rock-shaft 94 is mounted to turn in suitable bearings in the side webs 82 of the table 80 and carries a second arm 96, which is connected by means of a link 98, with the feed-slide 84. A spring 100 is coiled about the rock-shaft 94 and tends to swing the arm in a clock-wise direction, one end of the spring being secured to one of the shaft-bearings in the adjacent web 82, while its opposite end is secured to the arm 92. With this construction, the feed-slide 84 is yieldingly actuated by the spring 100, in a direction to advance the lifts toward the skiving mechanism, and is posi-

tively retracted by the cam 86 into position to advance another lift. The cam 86 is designed to permit the spring 100 to operate quickly so as to suddenly advance the feed-slide. This sudden advance of the feed-slide is a further precaution tending to prevent edgewise turning of the lifts as they are being advanced to the control of the feed rolls.

10 As the lowermost lift of the stack in the magazine 60 is advanced toward the skiving mechanism by the feed-slide 84, it is guided between a pair of guide members 102 (Fig. 1) that are arranged to engage the opposite lateral edges of the lift. The guide members 102 rest upon the table 80 and are adjustable toward and from each other by a right and left screw 104, the ends of which are held in yokes 106 that are mounted for 20 horizontal sliding adjustment on fixed guide-rods 108. As shown, the opposite ends of the guide-rods 108 are supported in ears 110 projecting laterally from the table 80 and suitable thumb-screws 112 are provided for 25 removably securing the guide-rods in place. A knurled head 114 furnishes means for turning the screw 104 to vary the distance between the guide members 102 so as to accommodate lifts of different widths. Upwardly extending fingers 116 (Fig. 3) on the guide members 102, are adapted to engage the opposite lateral edges of the lifts near the bottom of the stack in the magazine to align the lifts, vertically, and guide 35 them so that, as each lift reaches the bottom of the stack, it will be properly positioned between the guide members 102 to be engaged by the feed-slide 84 and advanced to the skiving mechanism.

40 In order to insure the feeding of only a single lift at a time from the supply magazine 60, at each operation of the feed-slide 84, a gate 120 (Figs. 3, 5 and 6) is provided which, in effect, closes the rear of the magazine. The gate projects into a vertical slot in the lower portion of the upright magazine member 62 and is arranged to yield upwardly to permit the lowermost lift to be fed from the magazine. To this end the gate is mounted for vertical sliding movement in ways formed between two guide-ribs 122, which are secured to the rear of the magazine member 62, and is forced downwardly by a pair of spring pressed plungers 124 which are severally confined in recesses formed within the guide-ribs 122. Secured to the gate is a vertical rod 126, which extends upwardly through suitable guideways formed in the magazine support 66. A nut 128 which is threaded upon the upper end of the rod 126 serves, by engagement with the top face of the adjacent guideway, to limit the downward movement of the gate under the influence of the spring pressed plungers 124. Normally the gate is positioned with its lower edge extending somewhat below the top face of the lowermost lift in the stack. The bottom face of the gate is bevelled at its forward edge, as indicated at 130 in Fig. 5, to permit the lowermost lift of the stack to be forced beneath the gate and raise the latter to permit the passage of the lift. Pivotally mounted in a vertical slot in the lower forward face of the gate is a finger 132, which extends to the bottom face of the gate and is spring-pressed so as to normally occupy the position in which it appears in Fig. 3. As the lift is being advanced by the feed-slide 84, the finger 132 is rocked upwardly by the lift before the lift raises the gate. When the gate has been raised by the lift, the finger 132 will swing back to its normal position and serve to prevent the lift immediately above the one engaged by the feed slide from being frictionally forced beneath the bevelled faces 130 of the gate. By turning the nut 128 on the upper end of the rod 126, the normal position of the gate with respect to the table 80 may be adjusted in accordance with the thickness of the lifts being operated upon, to permit the gate to operate to best advantage. The range of upward and downward movement of the gate is limited by the engagement of a stop-lug 134, on the gate, with the upper or lower end walls of a slot 136, in the magazine member 62, into which the stop-lug projects.

50 In order to overcome the tendency of the lifts to bend or curl upwardly as they are being skived, they are advanced beneath a lift-straightening or flattening device 140, (Fig. 3) which is carried by the bearing-blocks 36 of the upper feed roll. The lifts are held flat, by means of the lift-straightening device 140, against a support formed by the upper beveled face of the skiving knife 30 and the adjacent inclined support 42. A lift-straightening device of a similar nature, which is designed to cooperate with a support corresponding to the adjacent inclined upper faces of the skiving knife and the support 42, forms the subject matter of United States Patent No. 1,209,737, granted December 26, 1916, upon an application filed in the name of the present applicant. For a more detailed description of the arrangement of the lift-straightening device and the inclined supporting plates and a clearer understanding of the functions of these parts, reference may be had to said patent.

55 From the lift-straightening device 140 the lifts continue to advance upwardly across the inclined supporting plate 42 and finally drop into the front end of a magazine or receptacle 142, in which the lifts are to be stacked by means of a stacking device 144, as will presently be described. In practice it has been found that there is a tendency for the lifts to jump or tip upwardly as they continue to advance across the inclined

support 42, after passing beyond the lift-straightening device, and the leading lift on said support may rise above the plane of the following lift, by means of which it is being advanced. As a result, the leading lift may not drop into the magazine 142 so as to be acted upon at the proper time by the stacking device 144.

In order to insure that the leading lift on the inclined supporting plate 42 shall be maintained in the plane of the following lift, so that it will continue to be advanced thereby until it is pushed over the forward edge of the support 42, a stationary stabilizing finger 146 (Fig. 3) is located above said plate, and adapted to engage the top faces of the lifts as they pass beneath it, and prevent the lifts from tipping upwardly. The stabilizing finger 146 is adjustably secured, by means of a set-screw 148, to a stud 150 projecting rearwardly from the lift-straightening device 140. The stabilizing finger is adjusted on the stud so as to permit the lifts to tip and fall from the support 42 as soon as they have advanced far enough beyond the rear edge of the plate to over-balance. By loosening the set-screw 148, the stabilizing finger may be adjusted toward or from the rear end of the inclined support 42, in accordance with the length of the lifts operated upon, so that it may not interfere with the downward tipping of the lifts at the proper time.

The receiving magazine 142 into which the lifts drop after being advanced across the support 42 comprises a stationary horizontal base-plate or floor member 154 (Fig. 3) an upwardly inclined rear end-wall 156, that is formed integrally with the base-plate 154, and opposite side-walls which are adjustable toward and from each other to provide for lifts of different widths. The base-plate 154 is rigidly secured at one end to a supporting bracket 157 which is, in turn, secured to the frame of the machine. At its opposite end the base-plate 154 is supported by means of a post 158 which is adapted to rest upon the floor. The arrangement of the base-plate 154 and the integral end-wall 156 is such that the latter adjoins the rear end of the inclined support 42. The side-walls of the magazine 142 each consist of two horizontal wall sections 160 and 162, (Figs. 1 and 2) which are arranged end-to-end in alinement with each other.

The opposite side-wall sections 160 are arranged with their lower edges resting on the base plate 154 (see Fig. 4) and in order that said wall sections may be maintained in parallelism and adjusted laterally in unison, they are severally provided with outwardly and downwardly offset supporting arms 164, which are carried by a right and left screw 166 that is supported in bearings on the under side of the base-plate 154. A hand-

wheel 168 is secured to one end of the adjusting screw 166, by means of which the latter may be turned to adjust the side-wall sections 160. The front extremities of the side-wall sections 160 reach to the inclined end-wall 156 and are extended upwardly at 70 170 to the level of the top of the inclined support 42 to guide the lifts into the magazine as they drop from said support.

The side-wall sections 162 are also supported with provision for adjustment toward and from each other in accordance with the width of the lifts which are being operated upon. To this end the wall sections 162 are pivotally connected with the upper ends of separate pairs of supporting arms 172, (Figs. 1 and 2) said pairs of arms arranged on opposite sides of the base plate and being secured to separate rock-shafts 174. The rock-shafts 174 extend horizontally beneath the base plate adjacent opposite sides thereof and are adapted to turn in bearing brackets depending from the base plate. As shown, two of the supporting arms 172 which are arranged opposite each other on separate rock-shafts 174 are connected by means of a coiled spring 176 which tends to swing said arms and the wall section supported thereby toward each other. The forward ends of the wall sections 162 overlap the outer faces of the adjacent wall sections 160 (see Fig. 1) and the overlapping portions are held in contact with the latter by means of the spring 176. With this construction, the wall sections 162 are adjusted concurrently with the wall sections 160 by turning of the hand wheel 168.

In order that the lifts may be guided laterally during their passage across the inclined support 42, a pair of guide plates 180 (Fig. 3) are severally supported by the upward extension 170 of the side-wall sections 160, the lower portions of said guide plate being dove-tailed to the upper portions of said extensions 170 (see Fig. 4). These guide plates 180 extend as far forward as the lift straightening device 140 and provide for guiding the lifts after they leave the straightening device. To provide for guiding the lifts while passing beneath the straightening device 140 a pair of guiding fingers 182 are severally secured to the guide plates 180 in contact with the upper face of the support 42 and extend forwardly into close proximity with the upper feed roll. The opposed forward ends of the guiding fingers 182 are curved outwardly to facilitate the passage of the lifts between the fingers (see Fig. 1).

In order to provide for accurate adjustment of the guide plates 180 and the guiding fingers 182, a pair of adjusting arms 184 are carried by a right and left screw 186 (Figs. 1 and 3) and the forked lower 180

ends of the arms severally straddle the upper portions of the guide plates. The screw 186 extends horizontally above the guide plates 180 and is rotatably supported in bearing brackets 188 on the frame standards 14. The screw 186 is adapted to be rotated in unison with the screw 166 by means of a sprocket-chain 190 which passes over sprocket-wheels 192 and 194 on the screws 186 and 166, respectively.

As the lifts drop from the support 42 into the magazine 142 they come into the field of operations of the stacking device 144 by means of which they are to be stacked in the magazine 142. There is some tendency for a lift, as it falls into the magazine 142 to tip in such a manner that it will not come to rest in the proper position for the performance of the stacking operation, i. e., with its skived face in contact with the inclined end wall 156 of the magazine, but may be positioned with its lower edge resting upon the floor of the magazine at a point somewhat ahead of the face 25 of the inclined end wall. In order to insure that the lifts entering the magazine shall be positioned as required for the stacking operation, a lift-tipping device may be employed which tends to modify somewhat the falling movement of the lifts.

The lift-tipping device comprises a wheel 198, (Figs. 1 and 3) having a knurled or roughened periphery, which is continuously rotated about a horizontal axis and so positioned as to engage a breast edge of a lift as the lift is about to drop into the receiving magazine, and impart a downward blow to the lift so as to deflect the breast end thereof toward the inclined end wall 156. To this end the lift-tipping wheel 198 is secured on a shaft 200 which is journaled in a pair of arms 201 which embrace the wheel and curve upwardly and forwardly from a swing-frame 202. The swing-frame 202 is provided also with a pair of downwardly extending arms 203 which are arranged on opposite sides of the machine and are pivotally mounted on a horizontal rod 204 which extends transversely beneath the magazine and is secured to the base plate 154. The swing-frame 202 is supported in upright position by means of a thumb-screw 206, which is threaded into one of the downwardly extending arms, and extends 55 through an arcuate slot 208 (Fig. 2) in an arm 210 which is secured to the frame. By loosening the thumb-screw 206, the swing-frame 202 may be adjusted within the limits of the slot 208 to move the lift-tipping wheel toward or from the support 42, in accordance with the size of the lifts being operated upon, in order that it may properly perform its function.

The lift-tipping wheel 198 is driven from the power shaft 16 by means of a pair of

rope belts 212 and 214, the belt 212 passing over a pulley 216 fast on the power shaft and a pulley 218 which is mounted to turn on the rod 204, while the belt 214 also passes over the pulley 218, at one side of the belt 212, 70 and over a pulley 220 that is fast on the shaft of the lift-tipping wheel. It will thus be seen that the lift-tipping wheel is driven in such a manner that it may be adjusted toward and from the support 42 without interfering with its driving connections.

In order that the lifts may be maintained with one face in contact with the inclined end wall until operated upon by the stacking device 144, means is provided for preventing the lifts from slipping across the floor of the receiving magazine. For this purpose, a plate 222 (Figs. 3 and 4) having a roughened upper face is secured to the floor of the magazine adjacent the base of the end wall 156, so that it will engage the lower edge of the lift as it drops and prevent the lift from sliding along the floor of the magazine.

The stacking device 144 (Figs. 3 and 4) 90 comprises a pair of fingers 226 which are movable bodily through slots 228 in the end wall 156 and adjacent portion of the base plate 154 of the magazine. The stacking fingers 226 are formed, as shown in Fig. 3, with straight edges 230 for engaging the face of the lift lying on the inclined end wall 156. The fingers 226 project upwardly in parallelism with each other from the upper ends of an arm 232 to which they are rigidly secured and so disposed as to form a longitudinal extension of the arm. As shown in Fig. 4, the upper end of the arm 232 is bored to receive a sleeve 234 which is secured to the arm by a set screw 236. The stacking fingers 226 are mounted on the sleeve 234 at opposite sides of the arm 232. Over the projecting ends of the sleeve 234, outside of the fingers 226, are fitted collars 238. The collars 238, the fingers 226 and the arm 232, 100 are secured together by a plurality of pins 240 so that, in effect, said members constitute a single rigid arm.

The stacking device 144 is actuated by means of a crank-pin 242 carried by a crank-arm 244 on a crank-shaft 246, the crank-pin projecting through the sleeve 234 and the stacking device being retained on the crank-pin, between the crank-arm and the head of a screw 248, which extends axially into the outer end of the crank-pin, as shown in Fig. 4. The crank-shaft 246 is journaled in bearings in the bracket 157 and is driven from the power shaft 16 through the gear wheel 48 on the power shaft and an intermeshing gear wheel 252 on the crank-shaft 246. The lower end of the arm 232 of the stacking device is pivoted at 254 to one end of a link 256, the other end of which is pivoted at 258 to the bracket 157. With the lower end of the 110

stacking arm 232 thus mounted, the stacking fingers 226 are caused, by rotation of the crank-shaft in a clockwise direction, to move bodily through a substantially elliptical path by reason of which the straight edges 230 of the stacking fingers gradually assume a vertical position as they advance into the magazine. The stacking fingers consequently engage the lift which is resting 5 against the end wall 156 and advance it toward the other lifts in the stack, at the same time tilting it into substantially vertical position. Furthermore, the path of movement of the stacking fingers is such as to cause 10 them to enter the magazine 142 through the end wall portions of the slots 228 to engage the lift resting against the end wall, and to leave the magazine after completing a stacking operation, by a downward movement 15 through the rear portions of the slots 228 which are in the floor of the magazine. In this way the general direction of movement of the stacking fingers is never reversed within the magazine and consequently there 20 is no possibility of the stacking fingers interfering with the lifts as they drop from the support 42, and it is impossible for a lift to be caught between the stacking fingers and the end wall 156 as might happen 25 if the fingers oscillated back and forth within the magazine.

In order to prevent the lifts from falling away from the stack in the magazine 142 after they have been brought into stacked relation therewith, two sets of lift-retaining pawls 262 (Figs. 1 and 3) are provided for laterally supporting the end-most lift. These pawls 262 are pivotally mounted at their rearward ends on the side wall sections 160 30 of the magazine and are provided near their forward ends with lugs 264 which normally project through longitudinal slots into the magazine in the path of the lifts as the latter are moved forwardly by the stacking fingers. The lift-retaining pawls are yieldingly 35 pressed inwardly by means of spring-pressed plungers 266 which are confined within recesses at the rear portion of the pawls and engage lugs 268 on the side wall sections 40 160. As the lifts are advanced in the magazine by the stacking fingers, the margins of the lifts engage bevelled faces on the lugs 264 which yield outwardly under pressure and permit the lifts to pass beyond them. 45 The pawls 262 are then forced inwardly by the action of the spring-pressed plungers 266 and the lugs 264 by engagement with the rear face of the end-most lift prevent it 50 from falling away from the other lifts of the stack.

In order that the lifts which are acted upon by the stacking device at the beginning of the stacking operations may be retained in vertical position in the magazine, a pair of 55 thin spring plates 270 (Figs. 1 and 4) are

secured at their rear ends to the inner faces of the side wall sections 160. These springs normally converge toward their rear extremities sufficiently to frictionally engage the lateral edges of the lifts which have 70 been operated upon by the stacking device to hold these lifts upright until a sufficient number have accumulated in the magazine to provide lateral support for the newly stacked lifts.

During the movement of a lift under the influence of the stacking fingers, from the position in which it is supported by the end wall 156 to the upright position in which it is retained by the lift-retaining pawls 260, the lower or breast edge of the lift moves transversely across the roughened face of the plate 222. The plate serves during this movement of the lift to prevent the lower edge of the lift from slipping across the floor of the chute and thus tends to maintain the lift within the control of the stacking fingers, and to insure that it will be tilted into a substantially vertical position thereby.

The lifts when stacked in the magazine, 50 may be removed therefrom, still in their stacked relation, and conveniently introduced into the magazine of a machine which is adapted to operate automatically upon the lifts such, for example, as an automatic heel building machine.

While it is preferred to employ the specific construction and arrangement of parts herein shown and described it will be understood that this construction and arrangement is not essential, except so far as specified in the claims, and may be changed or modified without departing from the spirit and true scope of the invention.

What is claimed as new, is:—

1. In a machine for operating upon blanks, a magazine for holding the blanks in superposed relation, a reciprocating feed member for advancing the blanks one by one to the operating mechanism, and means for reciprocating the feed member, said means including a spring for causing the advancing movement, and a cam and co-operating roll for causing the retreating movement, the cam being shaped to apply tension gradually to the spring and then to permit the spring to advance the feed member quickly.

2. A stacking device for blanks having, in combination, a magazine having an end wall inclined to the floor thereof and adapted to receive the blanks, there being an opening located partly in said end wall and partly in said floor, a stacking member pivoted outside the magazine upon an axis which is transverse to the longitudinal axis of the magazine, and means for moving the blank contacting portion of said member into and out of said opening in a substantially elliptical path to push the blanks along 125 in the magazine.

3. In a machine for operating upon blanks of sheet material, a magazine constructed and arranged loosely to confine a stack of blanks, feeding mechanism for successively removing blanks from one end of the magazine and advancing them to the operating mechanism, guide members for engaging the blanks at their opposite lateral edges to guide them as they are advanced by the feeding mechanism, and means independent of the magazine for engaging the blanks as they approach the end of the magazine from which they are to be removed to direct them between said guide members. 70
- 10 4. In a machine for operating upon blanks of sheet material, a table for supporting a substantially vertical stack of blanks, a magazine constructed and arranged to loosely confine the stack, a feed device for advancing the lowermost blank in the magazine across the table to the operating mechanism, guide members for engaging said blank at its opposite lateral edges to guide the blank as it is advanced by the feed device, 75 and means on said guide members for engaging the blanks as they approach the lower end of the stack to direct them between the guide members. 80
- 15 5. In a machine for operating upon blanks of sheet material, a table for supporting a substantially vertical stack of blanks, a magazine having side walls constructed and arranged to confine the stack loosely between them, a feed device for advancing the lowermost blank in the magazine across the table to the operating mechanism, adjustable guide members for engaging said blank at its opposite lateral edges as it is advanced by the feed device, fingers rising 85 from said guide members for engaging the blanks at their opposite lateral edges as they approach the lower end of the magazine to direct them between the guide members, and means for adjusting the guide members toward and from each other to accommodate blanks of different widths. 90
- 20 6. In a machine for operating upon blanks of sheet material, means for feeding the blanks to and from the operating means, a magazine constructed and arranged to receive the blanks after they have been operated upon, said magazine having an inclined end wall adapted temporarily to support the blanks by engagement with a face thereof, and means for operating upon the blanks thus supported to stack them in upright position in the magazine. 95
- 25 7. In a machine for operating upon blanks of sheet material, a support across which the blanks are fed successively from the operating mechanism, a magazine arranged to receive the blanks after they have been fed across said support, the magazine having an inclined end wall adapted temporarily to support the blanks by engagement with a 100 face thereof, and a stacking member movable through said end wall for engaging the blank supported thereby and bringing it into upright position in stacked relation with the blanks previously delivered to the magazine. 105
- 30 8. In a machine for operating upon blanks of sheet material, mechanism for advancing the blanks successively from the operating mechanism, a magazine for receiving the blanks after they have been operated upon, said magazine having a substantially horizontal floor and an upwardly inclined end wall for supporting each blank by its lowermost edge and one of its faces respectively 110 as it is received in the magazine, means for operating upon the blanks thus supported to stack them in the magazine, and means for preventing the blanks from slipping across the floor of the magazine while resting against said end wall. 115
- 35 9. In a machine for operating upon blanks of sheet material, mechanism for advancing the blanks successively from the operating mechanism, a magazine for receiving the blanks after they have been operated upon, the magazine having an upwardly inclined end wall for supporting each blank in an inclined position as it is received in the magazine and a floor provided with a roughened portion for engaging the lowermost edges of the blanks to prevent the blanks from slipping across the floor, and means for operating upon the blanks thus supported to stack them in the magazine. 120
- 40 10. In a machine for operating upon blanks of sheet material, mechanism for advancing the blanks successively from the operating means, a magazine having a substantially horizontal floor and an upwardly inclined end wall constructed and arranged to receive the blanks after they have been operated upon and to support them temporarily in an inclined position, and an oscillating stacking finger movable through said end wall to bring the blanks into stacked relation with those previously received in the magazine. 125
- 45 11. In a machine for operating upon blanks of sheet material, mechanism for advancing the blanks successively from the operating means, a magazine having a substantially horizontal floor and an upwardly inclined end wall constructed and arranged to receive the blanks after they have been operated upon and to support them temporarily in an inclined position, said magazine also having an opening extending through the end wall and the floor, a stacking member adapted periodically to swing through the magazine to bring the blank supported by the end wall into stacked relation with those previously received in the magazine, the stacking member entering the magazine through the end wall portion of said open- 130

- ing and leaving the magazine through the floor portion of said opening, and means for actuating the stacking member.
12. In a machine for operating upon blanks of sheet material, mechanism for advancing the blanks successively from the operating means, a magazine for receiving the blanks after they have been operated upon, the magazine having a substantially horizontal floor and an inclined end wall for supporting the blanks in an inclined position as they are received in the magazine, means operating intermittently upon the blanks thus supported to position them vertically in the magazine, and means for preventing the blanks thus vertically positioned from tipping in either direction.
13. In a machine for operating upon blanks of sheet material, mechanism for advancing the blanks successively from the operating means, a magazine for receiving the blanks after they have been operated upon, the magazine having a substantially horizontal floor and an inclined end wall for supporting the blanks in an inclined position as they are received in the magazine, stacking means operating intermittently upon the blanks thus supported to position them vertically in stacked relation in the magazine, and means for frictionally engaging the blanks after they have been operated upon by said stacking means to retain them in stacked relation.
14. In a machine for operating upon blanks of sheet material, mechanism for advancing the blanks successively from the operating means, a magazine for receiving the blanks after they have been operated upon, the magazine being constructed and arranged to temporarily support each blank in an inclined position as it is received therein, stacking means operating upon the blanks thus supported to position them vertically in the magazine, and a pair of thin spring plates arranged to engage the opposite lateral edges of the blanks as they are brought into vertical position by the stacking means to retain the blanks in stacked relation.
15. In a machine for operating upon blanks of sheet material, mechanism for advancing the blanks successively from the operating means, a support across which the blanks are pushed by the advance of the blanks from the operating means, a magazine below said support into which the blanks drop after being pushed across said support, and a finger for holding the blanks downwardly against said support to maintain them in the plane of the blanks coming from the operating means, said finger being adjustable toward and from the end of the support in accordance with the size of the blanks being operated upon to avoid interference with the tipping of the blanks as they fall from said support.
16. In a machine for operating upon blanks of sheet material, a magazine for receiving the blanks after they have been operated upon, means for stacking the blanks in the magazine, a support extending between the operating means and the stacking means over which the blanks are pushed in series to the stacking means by the advance of blanks from the operating means, a device for preventing the blanks from curling while they are being operated upon, and means for holding the blanks downwardly against said support as they reach the delivery end thereof to maintain them in the plane of the following blanks.
17. In a machine for operating upon blanks of sheet material, a magazine for receiving the blanks after they have been operated upon, means for stacking the blanks in the magazine, a support between the operating means and the magazine across which the blanks are pushed to the stacking means by the advance of blanks from the operating means, a straightening device cooperating with that end of said support adjacent the operating means, and a stabilizing finger adjustable toward and from the straightening device for maintaining a leading blank in the plane of a following blank.
18. In a machine for operating upon blanks of sheet material, a support adjacent the operating means, mechanism for advancing the blanks successively from the operating means across said support until they fall from the end thereof, a magazine to receive the falling blanks, a stacking device for engaging each blank as it is received in the magazine and bringing it into stacked relation with the other blanks therein, and means for modifying the falling movements of the blanks properly to position them within the field of operations of the stacking device.
19. In a machine for operating upon blanks of sheet material, a support adjacent the operating means, mechanism for advancing the blanks successively from the operating means across said support until they fall from the end thereof, a magazine in which the blanks are to be stacked, the magazine being constructed and arranged to receive the falling blanks, and temporarily support them in a predetermined position preparatory to the stacking operation, a stacking device for engaging each blank as it is received in the magazine and bringing it into stacked relation with the other blanks therein, means for actuating the stacking device, and a rotating wheel constructed and arranged to strike the blanks a downward blow as they are about to drop into the magazine so as to cause them to assume the required position as they come to rest therein.
20. In a machine for operating upon blanks of sheet material, a magazine having

an upwardly directed mouth, a support for the blanks across which each blank is pushed until its forward portion overhangs the mouth, and means for engaging the forward end of the blank and tipping it down into the mouth of the magazine. 10

21. In a machine for operating upon blanks of sheet material, a magazine having

an upwardly directed mouth, a support for the blanks across which each blank is pushed until its forward portion overhangs the mouth, and a rotary member for engaging the forward end of the blank and tipping it down into the mouth of the magazine.

THOMAS LUND.
